US0D1059937S

(12) **United States Design Patent** (10) Patent No.: **US D1,059,937 S**
(45) Date of Patent: ** Feb. 4, 2025

(54) **COOKING APPLIANCE**

(71) Applicant: **StoreBound LLC**, New York, NY (US)

(72) Inventors: **Cheng Zhao**, Shenzhen (CN); **Yiyang Zhang**, Shenzhen (CN); **Shelby Scott**, New York, NY (US); **Evan Marc Dash**, New York, NY (US); **Ethan P. Kudler**, New York, NY (US)

(73) Assignee: **StoreBound LLC**, New York, NY (US)

(**) Term: **15 Years**

(21) Appl. No.: **29/886,839**

(22) Filed: **Mar. 14, 2023**

(51) LOC (15) Cl. **07-02**

(52) U.S. Cl. **D7/352**

(57) **CLAIM**

The ornamental design for a cooking appliance, as shown and described.

DESCRIPTION

FIG. 1 is a front perspective view of a cooking appliance showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrate portions of the cooking appliance that form no part of the claimed design.

1 Claim, 8 Drawing Sheets
